WINDOW STOP

Robert J. Kasik, Chicago, Ill.

Application July 8, 1947, Serial No. 759,564

6 Claims. (Cl. 292—342)

1

This invention relates generally to window stops and more particularly to a window stop which may be selectively positioned on a window.

In the prior art many attempts have been made to provide a window stop or sash lock which will be effective to prevent a window which is partially open from being further opened by someone from the outside. Various arrangements have been devised wherein wedges are fastened to the side rails of a sash by screws or other similar means to be engaged by a rail of the window sash. These arrangements have been objectionable both because the securing means mars the sash and because the stop is secured in a fixed position and cannot be adjusted to permit opening the window any amount desired.

It is, therefore, an object of the present invention to provide an improved window stop which may be adjustably positioned to permit opening the window any desired amount.

Another object of this invention is to provide a window stop which may be positioned on a window to limit the opening of the sash to a desired amount and which may be removably positioned on the window without marring the same.

A feature of this invention is the provision of a wedge-shaped window stop having a finger adapted to be positioned between the side rail of a window sash and the parting strip between the sashes for holding the stop in position.

A further feature of this invention is the provision of a window stop including a metal channel and a resilient wedge-shaped block positioned therein in which the channel includes a finger adapted to hold the stop in position to be wedged between the sashes of the window to limit the opening of the window.

A still further feature of this invention is the provision of a window stop including a metal channel with spurs on the sides thereof which dig into the sash to prevent movement of the stop when an attempt is made to force the window open.

Further objects, features and advantages will be apparent from a consideration of the following description taken in connection with the accompanying drawings in which:

Fig. 1 is a front view of a window on which a stop in accordance with the invention has been positioned;

Fig. 2 is a cross-sectional view along the lines 2—2 of Fig. 1;

Fig. 3 is a cross-sectional view along the lines 3—3 of Fig. 1;

2

Figs. 4 and 5 are perspective views of the window stops in accordance with the invention; and

Figs. 6 and 7 illustrate modified supporting fingers for window stops in accordance with the invention.

In practicing my invention I provide a window stop including a resilient wedge-shaped block and a metal channel in which the resilient block is supported. The wedge may be supported by being cemented in the channel or by the provision of integral lugs on the channel which can be bent to pierce the resilient block. The channel includes a finger which is adapted to be positioned between the side rail of a sash and the parting strip between the sashes of a window to hold the stop in position. This finger may include a prong to engage the sash or may extend around the edge of the sash to hold the stop in place. The metal channel includes spurs adjacent the top of the wedge which normally do not contact the side rail of the sash but which will be caused to dig into the side rail when excessive force is applied in an attempt to open the window against the stop.

Referring now to the drawings, in Figs. 1, 2 and 3 there is illustrated a window 10 including an upper sash 11 and a lower sash 12. The upper sash includes side rails 13, a top rail 14 and a bottom rail 15. The lower sash similarly includes side rails 16, a top rail 17 and a bottom rail 18. A lock 19 which may be of any standard construction is provided for locking the sashes when the window is entirely closed. A window stop 20 in accordance with the invention is secured to a side rail 13 to prevent opening the sash 12 more than a predetermined amount as will be explained.

In Figs. 2, 3 and 4 the detailed construction of the window stop 20 as well as the manner in which it may be used on a window is clearly illustrated. The stop includes a resilient block 21 which may be made of rubber or similar resilient material and a metal channel 22 in which the resilient block 21 is secured. The resilient block 21 is wedge-shaped and the metal channel 22 is similarly wedge-shaped with the sides 23 thereof covering only a portion of the sides of the resilient wedge. A plurality of integral lugs 24 are provided on the sides 23 which are bent in such a manner that they are imbedded in the resilient block to secure the block and channel together as a single unit. A finger 25 is provided on the channel 22 for holding the stop in position on the window. As clearly shown in Fig. 3, this

finger extends in the space between the side rail 13 of the sash 11 and the parting strip 26 between the sashes 11 and 12. In most windows this space is sufficiently small that a finger made of thin sheet metal will be held tightly therebetween so that the stop will be held in position on the side rail 13 of the sash. The surface of the resilient block 21 engages the surface of the sash and the friction between these members also helps hold the stop in position. The sides 23 of the channel also includes spurs 27 positioned at the thick end of the wedge, the spurs having pointed ends which extend almost to the surface of the resilient block. A clearance of $\frac{1}{16}$ of an inch has been found satisfactory in models tested.

With the window stop positioned on the upper sash as shown in the drawings, the amount which the lower sash can be raised is limited as clearly illustrated in Fig. 2. In this figure the lower sash 12 is shown in dot-dash lines in the uppermost position to which it can be raised with the window stop 20 in place. It will be noted that the edge 28 of the upper rail 17 of the sash 12 engages the back of the metal channel 22 so that the window cannot be further raised. It is apparent that if the window sash 12 is raised further so that the upper rail 17 thereof is pushed against the stop 20 with relatively great force, the resilient block 21 will be compressed and the spurs 27 of the channel will dig into the surface of the side rail 13 so that the stop acts positively to prevent further opening of the sash 12. As previously stated, the spurs are normally a slight distance from the side rail 13 as, for example, $\frac{1}{16}$ of an inch and will, therefore, not normally engage the rail. It is only in emergencies when the lower sash is raised with great force that the spurs would be effective to dig into the side rail.

It is obvious that the stop 20 can be positioned in any desired position on the side rail 13 to thereby limit the opening of the lower sash to any desired point. This makes it possible to raise the window different amounts as may be desired depending upon the temperature outside a room. This is important as the stop is most effective when it is placed so that it will be engaged by the lower sash when the sash 12 is open.

As is well known, in older houses the window sashes normally fit more loosely and, therefore, a straight finger as illustrated in Fig. 4 might not fit tight enough between the side rail 13 and the parting strip 26 of the window to hold the stop in place. In such cases a prong may be punched in the finger to engage the side rail 13 of the upper sash 11. In Fig. 6 a modified finger 30 is shown having a prong 31 therein. It is noted that the finger 30 is curved slightly so that the prong will be held against the side rail of the upper sash when the stop is in position. As the curved finger 30 provides a spring action, the prong 31 can be very small and still be effective to hold the window stop in position on the window. It has been found that a prong only about twenty-thousandths of an inch long is adequate to hold the stop in position. It is to be pointed out that the prong 31 is not for the purpose of holding the stop against movement when it is engaged by the lower sash but is used only to hold the stop in position when the stop is not actually in use. When the stop is engaged by the lower sash the wedging of the stop between the sashes locks the stop in position and prevents

further movement of the lower sash as previously described. As the prong is very short it does not prevent adjustment of the position of the stop on the window. Further the prong does not 5 objectionably mar the window, as the prong engages the side rail underneath the parting strip and any scratching of the side rail caused by the prong will be hidden by the parting strip.

In addition to holding the stop in position on the window, the prong 31 on the holding finger 30 is effective to hold the stop stationary with respect to the upper sash 11 when the sash is moved up and down. This provides an additional 10 advantage as it limits the downward movement 15 of the upper sash. Therefore, it is seen that the stop is effective to prevent unintentional lowering of the upper sash 11, as when the sash 11 is pulled down the stop will engage the top rail 17 of the lower sash to prevent further opening 20 of the top sash.

In Fig. 7 there is shown a further modification of the finger of the stop. In this figure the finger 35 is L-shaped having a portion 36 extending around the corner of the side rail 13. In this 25 case the stop would have to be inserted by lowering the upper sash and inserting the stop from the top of the window. The portion extending around the edge of the side rail would bear sufficiently against the rail to prevent the stop 30 from slipping out of the window or sliding with respect thereto. A stop with such a finger would also work well in a relatively loose window as stated above.

It is to be pointed out that the resilient wedge 35 21 can be secured to the channel 22 in any suitable manner other than by the use of lugs 24. For example, the resilient member may be cemented in the channel as shown in Fig. 5. Also the stop may take various other configurations than that illustrated in the drawing and the parts thereof can be made of any suitable material, not being limited to the materials mentioned.

It is seen from the above that I have provided a very simple and inexpensive window stop which may be placed on the upper sash at any desired position to limit the opening of the lower sash. As the position of the stop can be changed as desired, it will be effective to limit the opening of 45 50 the lower sash to the amount desired. The stop does not need to be permanently secured to the sash and will not mar the sash as the sash is normally engaged only by the surface of the resilient block.

55 While I have described what I consider to be the preferred embodiments of my invention, it is apparent that various modifications and changes can be made therein without departing from the intended scope of the invention as defined in the 60 appended claims.

I claim:

1. In a window including movable upper and lower sashes and a parting strip between said sashes, a wedge-shaped stop for limiting the movement of said lower sash including a finger adapted to be positioned between said upper sash and said parting strip for holding said stop in any desired position on said upper sash, said finger having a prong thereon and being curved so that said prong engages said upper sash, said stop being arranged to be wedged between said upper and lower sashes when it is engaged by said lower sash to thereby limit the movement thereof.
2. A window stop including a wedge-shaped

resilient block and a metal channel supporting the same, said channel including a finger adapted to be positioned between the upper sash and the parting strip of a window to hold said stop in any desired position thereon, said channel being arranged to be engaged by the lower sash of said window when it is raised to prevent said lower sash from being raised more than a predetermined amount.

3. A window stop including a wedge-shaped resilient block and a metal channel supporting the same, said channel including integral lugs for holding said block thereon and a finger adapted to be positioned between the upper sash and the parting strip of a window to hold said stop in any desired position thereon, said channel being arranged to be engaged by the lower sash of said window when it is raised to prevent said lower sash from being raised more than a predetermined amount.

4. A window stop including a wedge-shaped resilient block and a metal channel supporting the same, said channel including a finger adapted to hold said stop in any desired position on the upper sash of a window, said stop being arranged to be wedged between the upper and lower sashes of said window when said channel is engaged by said lower sash, said channel including spurs normally held away from said upper sash by said resilient block but engaging said upper sash when said lower sash is urged against said stop with great force.

5. In a window including movable upper and lower sashes and a parting strip between said

sashes, a wedge-shaped stop for limiting the movement of said lower sash including a finger adapted to be positioned between the side rail of said upper sash and said parting strip for holding said stop in any desired position along said side rail, said finger being curved and having a prong thereon which is positioned to engage said side rail, said curved finger holding said prong in engagement with said side rail so that said stop moves with said upper sash.

6. In a window including movable upper and lower sashes and a parting strip between said sashes, a wedge-shaped stop for limiting the movement of said lower sash including a finger adapted to be positioned between the side rail of said upper sash and said parting strip for holding said stop in any desired position along said side rail, said finger being curved and having a prong thereon, said prong being positioned on said finger so that it engages the portion of said side rail which is covered by said parting strip to thereby prevent marring of said upper sash.
